US00D860432S

(12) **United States Design Patent** (10) Patent No.: **US D860,432 S**
Badarello (45) Date of Patent: **** Sep. 17, 2019**

(54) **CANOPY FOR A CEILING FAN**(71) Applicant: **HUNTER FAN COMPANY**,
Memphis, TN (US)(72) Inventor: **Christophe Badarello**, Holly Springs,
MS (US)(73) Assignee: **Hunter Fan Company**, Memphis, TN
(US)(**) Term: **15 Years**(21) Appl. No.: **29/634,059**(22) Filed: **Jan. 18, 2018****Related U.S. Application Data**(62) Division of application No. 29/557,368, filed on Mar.
8, 2016, now Pat. No. Des. 816,676.(51) **LOC (12) Cl.** ..... **23-03**(52) **U.S. Cl.**USPC ..... **D23/411**(58) **Field of Classification Search**USPC D23/249, 252, 254, 370-385, 411-414;
